UNITED STATES PATENT OFFICE.

SALVATORE ADRAGNA, OF BUFFALO, NEW YORK.

WATER MOTOR.

Application filed June 20, 1927. Serial No. 199,993.

This invention relates to a water motor which is more particularly designed for operating a grinding or polishing wheel by motion derived from the water pressure of a kitchen faucet and it is the object of this invention to provide such a motor which can be readily mounted and unmouted in a kitchen sink and permit of conveniently and expeditiously sharpening knives or polishing various kinds of cutlery and household articles.

In the accompanying drawings:

Figure 1 is a vertical cross section of a kitchen sink, on a reduced scale, equipped with an approved form of my invention. Figure 2 is a vertical cross section, on an enlarged scale, taken on line 2—2, Fig. 1. Figure 3 is a horizontal section taken on line 3—3, Fig. 1. Figure 4 is a fragmentary vertical longitudinal section taken on line 4—4, Fig. 5 is a fragmentary vertical cross section taken on line 5—5, Fig. 4. Figure 6 is a fragmentary vertical longitudinal section taken on line 6—6, Fig. 2. Figure 7 is a vertical section taken on the correspondingly numbered line in Fig. 1.

Similar characters of reference indicate like parts in the several figures of the drawings.

This water motor is more particularly intended for use in a kitchen sink 10 arranged next to a back wall 11 from which a water supply faucet 12 projects over the sink.

The means whereby rotary motion is obtained by the pressure of the water from the faucet consist generally of a casing 13 and a water wheel 14 rotating within the casing. On one side of the lower peripheral part of the casing the same is provided with a radial extension 15, one side of which has an inlet pipe 9 adapted to be connected by an external coupling 16 with the spout of the water supply faucet, as shown in Fig. 1. On its opposite side this extension is provided with an outlet pipe 17 whereby the water which has spent its power in driving the water wheel is carried away from the casing and discharged into the sink.

The water wheel is preferably constructed from a sheet of metal which forms a central disk 18 and a plurality of buckets 19 arranged in an annular row around the axis of the water wheel. The inlet pipe is provided within the casing with a nozzle 8 which directs the water in the form of a jet

or small stream against the buckets of the water wheel so that the latter is turned as the water impinges successively against the buckets. The water wheel is mounted on the inner end of a horizontal longitudinal shaft 20 which is journaled in a bearing 21 on the front wall of the casing. In front of the casing is arranged a supporting bracket which preferably comprises two longitudinal side bars 22, 23, arranged parallel with and on opposite sides of the shaft and secured at their inner ends to the front wall of the motor casing and a cross bar 24 which connects the outer ends of said side bars and which is provided with a bearing 25 in which the outer end of the shaft is journaled. Upon this shaft is mounted a tool, for example, an operating wheel 26 which may be of any suitable form so as to perform the operations of grinding, polishing or buffing. As shown in the drawings the wheel 26 has the form of a grindstone or carborundum wheel but obviously the same may be replaced by one of different form or material.

The article to be sharpened, ground, polished or buffed, for example, a kitchen knife, may be engaged either with the periphery or the opposite sides of the grinding wheel while the shaft supporting the wheel is rotated by the stream of water from the faucet impinging against the buckets of the water wheel.

For the purpose of holding a knife or other implement in the proper position against either side of the grinding wheel two supports or rests are provided each of which consists of a channel shaped seat 27 arranged transversely on one side of the grinding wheel and provided at its inner and outer ends with loops 28, 29, which are bent around the adjacent part of the shaft and the adjacent part of one of the side bars of the bracket. Each of these supports or rests may be slid lengthwise on the shaft and the bracket to suit the character of the element to be ground or polished. In the case of a knife the back edge of the blade engages the channel seat while its cutting edge is tilted into engagement with the side of the grinding wheel for sharpening or dressing the same.

The front end of the bracket is provided with a brace whereby the same may be supported on the bottom of the sink or other surface while the grinding wheel is in use.

This brace is preferably U-shaped and comprises two normally upright bars 30, 30, connected at their upper ends with the front part of the bracket side bars and a cross bar 31 connecting the lower ends of the upright bars and adapted normally to rest on the bottom of the sink, as shown in Figs. 1 and 7.

The connection between the upper ends of the brace side bars and the bracket side bars is preferably of such character that the brace can be folded relatively to the bracket and also adjusted vertically relatively thereto, this being accomplished in the present instance by bolts 32 arranged on the side bars of the bracket and passing through vertical slots 33 in the side bars of the brace. By these means the position of the brace relative to the bracket may be adjusted vertically to permit of mounting this apparatus on sinks in which the relation of the water faucet and the bottom of the sink varies, and it also permits of folding the brace relative to the bracket so as to render the apparatus more compact for convenience in transportation and storage.

As a whole, this apparatus is very simple and durable in construction, it has no delicate parts which are liable to get out of order, it can be readily installed for use, and the same permits of conveniently and expeditiously sharpening, grinding or buffing the various implements usually employed in a household.

35 I claim as my invention:

1. A water motor comprising a casing having a water inlet and outlet, a water wheel within said casing having buckets adapted to be impinged by a stream of water from said inlet, a shaft extending through said casing and connected at its inner end with said wheel and adapted to support a tool on the exterior thereof, a bracket projecting laterally from said casing, and pro-

vided with a bearing in which the outer end 45 of said shaft is journaled, and a brace extending downwardly from said bracket and adapted to rest on a support, and having two upright side bars connected at their upper ends with said bracket and a cross bar connecting the lower ends of said upright bars. 50

2. A water motor comprising a casing having a water inlet and outlet, a water wheel within said casing having buckets adapted to be impinged by a stream of water from said inlet, a shaft extending through said casing and connected at its inner end with said wheel and adapted to support a tool on the exterior thereof, a bracket projecting laterally from said casing and provided with a bearing in which the outer end 55 of said shaft is journaled, and a brace extending downwardly from said bracket and adapted to rest on a support and pivotally connected with said bracket so as to be foldable relatively thereto. 60

3. A water motor comprising a casing having a water inlet and outlet, a water wheel within said casing having buckets adapted to be impinged by a stream of water from said inlet, a shaft extending through said casing and connected at its inner end with said wheel and adapted to support a tool on the exterior thereof, a bracket projecting laterally from said casing and provided with a bearing in which the outer end 70 of said shaft is journaled, and a brace extending downwardly from said bracket and adapted to rest on a support, and having two upright side bars connected at their upper 75 ends with said bracket and a cross bar connecting the lower ends of said upright bars, said upright bars having vertical slots and said bracket having bolts passing through said slots. 80

85 In testimony whereof I affix my signature.

SALVATOREADRAGNA.
